UNITED STATES PATENT OFFICE.

RICHARD TOLOOKJIAN, OF PATERSON, NEW JERSEY.

ROTARY WASHER.

1,414,605.

Specification of Letters Patent. Patented May 2, 1922.

Application filed June 1, 1921. Serial No. 474,160.

To all whom it may concern:

Be it known that I, RICHARD TOLOOKJIAN, a citizen of the United States, residing at Paterson, in the county of Passaic and State of New Jersey, have invented certain new and useful Improvements in Rotary Washers, of which the following is a specification.

This invention has relation to brushing and cleaning devices, and has for an object to provide a device embodying a brush mounted for rotation, a water wheel forming part of the brush and a water jet directed upon the water wheel whereby the brush may be rotated and applied to the article to be cleaned.

Another object of the invention is to provide a rotary cleaning device which comprises a hollow-frame in which a rotary brush is mounted carrying a water wheel and a jet directed against the wheel, part of the water entering the frame where it is admixed with a detergent and issuing again through fine openings against the brush.

In addition to the foregoing this invention comprehends improvements in the details of construction and arrangement on parts to be hereinafter described and particularly set forth in the appended claims.

In the accompanying drawings in which similar and corresponding parts are designated by the same characters of reference throughout the several views in which they appear:

Figure 1 is a view in transverse section of a rotary washer constructed in accordance with my invention,

Figure 2 is a view thereof in top plan.

With reference to the drawings, 10 indicates a hollow casing, crescent shaped in cross section and having a pair of extensions 11 and 12 at each end. Mounted between the extensions upon pivot screws 13 is a cylindrical brush 14, said screws penetrating the extensions and entering the ends of the brush. Also mounted upon said screws and located between the extensions 11 and 12 at each end of the frame is a wheel 15 of a diameter corresponding to the brush. The medial portion of the brush is free of bristles to permit the location thereon of a water wheel 16. The water wheel construction consists of a plurality of caps 17 having curved bottoms 18 to conform to the curvature of the brush roller, end walls 19

which are radial relative to the center of curvature of said bottoms and side walls 20. The cups are secured upon the brush in end to end relation by means of the screws 21, thus defining a circular water wheel in which the end walls 19 form the vanes and the side walls 20 annular flanges, located between the adjacent end walls of each pair of adjacent cups is a strip of rubber 22 which extends to the periphery of the bristles and prevents injury to the object to be cleaned by preventing contact of the water wheel with the object. A coupling 23 is attached to the casing whereby a hose from a source of water supply may be attached thereto to permit water to enter the casing. Located in the casing is a tube 24 having one end in the coupling and the other extending through the inner wall of the casing and directed against the water wheel 75 in a direction tangential relative thereto to form a jet. A series of fine openings 25 are formed in the inner wall of the casing to direct streams of water against the bristles. A small water wheel 26 is mounted 80 in the casing and a jet 27 is directed against said wheel and is fed from the coupling 23.

In use, the water entering the coupling will be divided, part entering the jet 24, part entering the jet 27 and part entering 85 the casing 10. A detergent such as small pieces of soap is placed in the casing and owing to the rotation of the wheel 26 suds will be formed, and the soapy water will issue from the openings 25 and moisten the 90 bristles. At the same time the water issuing from the jet 24 will strike the vanes 19 of the water wheel and rotate the brush which is applied to the object to be cleaned. The abrasive action of the brush combined 95 with the flushing of the water will thoroughly clean the object.

Thus, it will be seen that I have provided a novel form of rotary washer which is particularly adapted for washing automobile 100 bodies, carriages, railway cars, etc., with effective results and without injury to the surface of the object. Other uses and advantages will readily occur to those familiar with the art to which this invention appertains.

While I have illustrated and described my invention with some degree of particularity, I realize that in practice various alterations therein may be made.

Having thus described my invention, what I claim as new and desire to secure by United States Letters Patent is:

- 5 1. A rotary washer including a hollow casing, a brush mounted thereon for rotation, a plurality of radial vanes carried by the brush, said casing having a series of openings in one wall, a jet extending through the casing and directed against the vanes, and a coupling to supply water to the jet and casing.
- 10 2. A rotary brush including a hollow casing, crescent shaped in cross section, an ex-

tension at each end, a brush mounted between the extensions and located in the concave portion of the casing, radial vanes mounted on the brush, radial rubber strips mounted on the vanes and extending to the periphery of the brush, a jet, and a coupling for supplying water to the jet and casing. 15 20

In testimony whereof I affix my signature in presence of two witnesses.

RICHARD TOLOOKJIAN. [L.S.]
